H. D. HUME ET AL

Re. 21,604

HARVESTER

Original Filed Nov. 18, 1935

UNITED STATES PATENT OFFICE

21,604

HARVESTER

Horace D. Hume and James E. Love, Garfield,
Wash., assignors to Hume-Love Company, Gar-
field, Wash., a corporation

Original No. 2,102,710, dated December 21, 1937,
Serial No. 50,389, November 18, 1935. Appli-
cation for reissue December 18, 1939, Serial No.
311,924

2 Claims. (Cl. 56—158)

Our present invention relates to improvements in harvesters or mowers of the sickle, or front, outwardly-set, reciprocating cutter type, with which is combined a draper, or conveyer located 5 at the rear of the sickle and disposed trans- versely of the implement. The draper or end- less-belt conveyer is mounted on a draper frame that may be hinged or adjustably supported by the main frame of the implement, and the cutter 10 or sickle is suspended from the draper frame to provide freedom of movement within a limited range of the reciprocating cutter in order to compensate for irregularities in the surface of the ground over which the implement is advancing. 15 The draper and its frame may remain in sta- tionary position with relation to the implement, while the sickle or reciprocating cutter is sup- ported from or suspended from the draper frame for upward and downward movement. 20 By the combination and arrangement of parts according to our invention, the cutter bar or sickle is disposed in operative position close to the ground for effective work, and the whole of the cut crop is cleanly and neatly passed rear- 25 wardly and upwardly to the draper and conveyed thereby to other parts of the implement or dis- posed of in suitable manner. The implement is effective not only for harvesting standing grain, but is also specially adapted for cutting down or 30 fallen grain, vines, and other crops that lie close to the ground.

Our invention consists in certain novel com- binations and arrangements of parts as will here-inafter be more fully set forth and claimed. 35 In the accompanying drawing we have illus- trated one complete example of the physical em- bodiment of our invention in which the parts are combined and arranged according to one mode we have so far devised for the practical applica- 40 tion of the principles of our invention, but it will be understood that changes and alterations may be made in these exemplifying structures, within the scope of our claims, without departing from the principles of our invention.

45 Figure 1 is a view showing the draper frame with the draper in transverse section, and illus- trating the sickle and the means by which it is mounted or suspended from the draper frame and supported on the surface of the ground,

50 Figure 2 is a fragmentary, top plan view, at the outer end of the cutter bar, showing its support- ing arm, and also a guide bar which guides ex- cess grain out of the swathe to be cut,

55 Figure 3 is a perspective view showing the for- wardly and upwardly projecting guide bar mount-

ed on the cutter bar, one of the tines over which the cut grain is passed to the draper, and a portion of the supporting arm for the cutter bar,

Figure 4 is a broken view in perspective of the supporting arm, and

Figure 5 is a view similar to Figure 1 but with a slightly modified arrangement of the supporting arm, and of the tines.

The draper frame 1, which is or may be of rec- tangular shape and disposed above the ground at 10 a slight forwardly declining angle, is supported on a tubular frame bar 2 that extends trans- versely of the implement, and the frame is at- tached to the bar as by U-bolts 3. On top of the draper frame are fixed a pair of parallel angle 15 bars 4 and 5 which extend transversely of the implement, and the usual rollers 6 for the draper 7 are journaled in bearing blocks B mounted in these front and rear bars. The draper is of the endless belt type, preferably of canvas, and it 20 is provided with spaced slats 8 that assist in conveying the cut grain transversely of the im- plement as it is received from the apron 9 of Figure 1.

The apron 9 in Figure 1 may take the form of 25 a sheet metal plate that is attached or fastened at 10 at the top front edge of the draper frame, the upper edge of the apron being approximately flush with the top of the draper, and the apron projects forwardly of the frame and declines 30 therefrom at an angle of approximately forty- five degrees, more or less.

The cutter bar 12, with its reciprocating teeth 13, is connected at its inner, or implement-end, 35 in suitable manner, and usual mechanism is em- ployed for reciprocating the cutter. As indicated in Figures 1 and 5, the cutter bar lies close to the surface of the ground in advance of the draper and the draper frame, and normally be- low the plane of the draper frame.

To separate grain from the swathe to be cut, 40 to lift the fallen crop, and to prevent crushing of the crop outside of the swathe to be cut, we provide a guard-finger, guide bar, or separator 14, which is rigidly fastened, as by welding, at 15, to a finger guard of the cutter bar. This separator 45 as indicated, projects forwardly in advance of the cutter bar, and it curves upwardly and inwardly toward its free end, so that the advancing sep- arator entering the grain, will gradually push 50 some of the grain from the outer edge of the swathe, and separate the grain to be cut there- from in order that a well-defined line of cleav- age may be made by the cutter in the swathe, without unnecessary loss of the crop. The up- 55

ward curve of the separator tends to lift and hold erect the fallen grain and guides the grain to the cutter, while the lateral curve in the separator tends to pass the separated grain outwardly and away from the cutter, thus preventing an excess of grain in front of the cutter that would result in tangling the crop and clogging of the cutter.

As the grain is cut, the cut grain rides upward-
ly and rearwardly from the cutter over a row
of tines or fingers 16 that are spaced at regular
intervals with their front ends attached at the
rear edge of the cutter bar. These tines are in-
clined on approximately the same angle as the
apron 9, and the rear, free ends of the tines over-
lap the front or lower edge of the apron so that
the cut grain may ride smoothly up over the tines
and the apron and be deposited on the draper.

At its outer end, and at spaced intervals with
long cutter bars, the cutter bar is supported by
means of arms 17. The rear end of such an arm
is pivoted at 18 to the draper frame, and this arm
is fashioned with a rounded or convex shoe por-
tion 19 that frictionally engages and slides over
the surface of the ground as the implement ad-
vances. The pivotal support 18 at the rear end
of the arm is located toward the rear of the
draper frame and the arm extends forward, de-
clining to the ground below the frame, the
bowed or curved shoe portion of the arm being
located approximately below the front edge of
the draper frame, and at the rear of the cutter
bar.

Above the shoe or runner 19 of the pivoted bar
or arm 17, a bracket arm 20 is fastened to and
projects in front of the draper frame, and this
bracket arm is fashioned with a series of spaced
bolt holes 21, for the attachment of a chain 22,
which chain is also attached at 23 to the sup-
porting arm at the rear of the cutter bar. By
means of the series of bolt holes in the bracket
arm and the chain, the suspended arm may be
adjusted with relation to the draper frame, and
as the cutter bar is fastened to the front end
of the supporting arm, the cutter bar is also ad-
justed, with the supporting arm, with relation
to the surface of the ground.

As indicated in Figure 4, the supporting arm,
which is fashioned of an angle bar, at its front

end is provided with a reinforcing angle bar 17'
rigidly attached to the supporting arm, and the
front end of the supporting arm is fashioned with
spaced perforated lugs 24, and an overhanging
head 25, which form a notch 26. This notched-
head of the supporting arm is slipped over the
rear edge of the cutter bar, and the lugs 24 are
securely bolted to the cutter bar to provide a
rigid and secure fastening between the supporting
arm and the cutter bar. The supporting arm 10
thus provides a rearwardly pivoted support for
the cutter bar and insures an up and down move-
ment of the cutterbar as the shoe or runner
passes over irregularities in the surface of the
ground, and the suspending chain 22 limits this 15
movement within proper range.

In Figure 5 the apron 9 is omitted, and the tines
16' extend up to the front edge of the draper
frame, and the supporting arm 17 is bolted at its
front end to the cutter bar, and provided with a 20
resilient and flexible shoe or runner 19' of spring
steel or other suitable material, for the perform-
ance of the functions of the shoe portions 19 of
the supporting arm 17 of Figure 1.

Having thus fully described our invention, what 25
we claim as new and desire to secure by Letters
Patent is:

1. In a harvester implement of the reciprocal
cutter type, the combination with a relatively
stationary supporting frame and a separate ver-
tically movable cutter bar in advance of the
frame, of a supporting arm attached to said 30
cutter bar and pivoted to the frame, said arm
having a ground shoe, a bracket arm mounted
forwardly of the frame having a series of bolt
holes, a chain attached to the forward end of
the arm, and a bolt fastening said chain to the
bracket arm. 35

2. In a harvesting implement the combination
with a relatively stationary frame, and a sepa-
rate vertically movable cutter bar in advance of
the frame, of a supporting arm hinged to said 40
frame and having a pair of spaced attaching
lugs on the arm fixed to said cutter bar, an
overlapping head on the arm frictionally engag-
ing the cutter bar, and a flexible connection be-
tween said arm and a forward part of the frame. 45
